UNITED STATES PATENT OFFICE.

SAMUEL W. CHARLES, OF PALO ALTO, CALIFORNIA.

RAZOR.

1,105,756.

Specification of Letters Patent.

Patented Aug. 4, 1914.

Application filed June 27, 1911. Serial No. 635,591.

To all whom it may concern:

Be it known that I, SAMUEL W. CHARLES, of the city of Palo Alto, county of Santa Clara, State of California, have invented a new and useful Improvement in Razors, of which the following is a specification.

The primary object of my invention is to provide a simple and novel razor, the blade of which may be correctly stropped without removing it from its holder in the razor frame.

The invention consists in the construction and arrangement of parts which will be fully hereinafter specified in preferred form.

In the drawing Figure 1 is the top plan view of a razor embodying the features of the invention in position on the strop for stropping. Fig. 2 is a side view corresponding to Fig. 1 except that the near half of the pulley clip is removed. Fig. 3 is a partial rear view of the razor with pulley clip attached, one end of the clip being distorted to show the square hole in the pulley.

The constituent parts of the razor are the frame A to which are attached the handle B and combed guard plate C.

D is a cylindrical shaft and rests in slots V in frame A. Slots V are rounded at their inner extremity in frame A so as to permit shaft D to freely turn when the razor is placed in clip T for stropping.

I is the blade and is held in a slot in bladeholder H. The bladeholder H is rigidly attached to shaft D. The blade is held against the guard C in a position for shaving by movable latch fingers G, the hooked ends of which project over each corner of the blade. The latch fingers are held in locking position by spring K which is fastened to handle B. The blade is released by pressing together the two latch handles J which spread apart the fingers G. The blade I may be then swung clear of the guard plate C for stropping or cleaning or may be removed from the frame by slipping the shaft D out of the slots V.

L is a bar in frame A and serves to maintain proper relation between strop and blade in the act of stropping. The strop, that is preferably employed consists of a clamp M to which are attached strop N and cords P. These cords pass through openings Q in clamp M.

T is a steel frame or steel clip of spring material. Held in this clip are two pulleys

F which are free to rotate in the clip and have square holes through their centers to engage the projecting ends of shaft D which are squared to receive them. The clip is attached to the strop by wrapping the cords once around their respective pulleys in such a manner that the cords approach and leave the pulleys at the top as shown in Figs. 1 and 2.

To strop the razor, the razor is placed in the pulley clip T by slipping its handle B through the hole therein and springing apart the pulleys F so that the squared ends of shaft D may be fitted into the squared holes in pulleys F. The spring in clip T will hold the squared ends of shaft D firmly in their places in pulleys F while stropping. The blade is released by pressing together the two latch handles J which spread apart the latch fingers G. Pass the strop through the razor frame under the bar L. With the other hand move the razor forward and backward along the strop by means of its handle B. The action of the cords on the pulleys causes the blade to extend in the direction opposite to that in which the razor is moving and to be dragged in stropping position along the strop N. The pressure of the blade against the strop is regulated by the tension put upon the cords by the hand holding them. Upon reaching the end of a stroke the return stroke is begun but the action of the cords upon the pulleys is such that the blade is swung into proper position the instant the return stroke is begun. The swinging of the blade upon a reversal of the stroke is timely and positive thus effectually preventing any cutting of the strop. The razor may be removed from clip T by springing apart the pulleys F and disengaging the squared ends of shaft D from the pulleys. The projecting ends of shaft D may be triangular, polygonal, or of irregular shape in which event the holes in the pulleys must be made to match.

I do not limit myself to the exact details described above. It will be understood that the details of construction may be varied slightly to facilitate or cheapen manufacture.

Having thus described the nature and objects of my invention and the manner of its operation, what I claim as new and desire to secure by Letters Patent is:

1. In a razor, the combination with a supporting frame, of an oscillatory blade holder

5 journaled therein and having a blade receiving slot, and opposite reciprocatory latches engaging over the cutting edge of the blade and having overlapped offset portions forming finger pieces that are movable toward and from each other.

10 2. In a razor, the combination with a frame having a handle and a comb plate, of an oscillatory blade holder mounted on the frame, a blade detachably mounted in the holder and having a cutting edge located at the margin of the comb plate, and oppositely-acting latches slidably mounted on the

rear side of the comb plate and provided with offset finger pieces that are movable 15 toward each other, said latches having hooks that detachably engage over the blade to hold the latter in position on the comb plate and being movable outwardly upon the movement of the finger pieces toward each 20 other.

SAMUEL W. CHARLES.
